Int. Cl. D9—04

U.S. Cl. D9—235

Fig. 1

Fig. 3

Fig. 2

Fig. 4

Fig. 5

Fig. 6

Fig. 7

FIG. 1 is a perspective view of a container for sewing machine attachments showing our new design;

FIG. 2 is a top plan view thereof;

FIG. 3 is a side elevation view thereof as seen from the left in FIG. 2;

FIG. 4 is a front elevation view thereof;

FIG. 5 is a side elevation view thereof as seen from the right in FIG. 2;

FIG. 6 is a bottom plan view thereof; and

FIG. 7 is a rear elevation view thereof.

We claim:

The ornamental design for a container for sewing machine attachments or similar article, substantially as shown.
